UNITED STATES PATENT OFFICE.

ALFRED G. HAGUE, OF ADEL, IOWA, ASSIGNOR TO HALVER R. STRAIGHT, OF ADEL, IOWA.

OFF-BEARING MECHANISM FOR TILE CUTTERS.

1,411,492.

Specification of Letters Patent.

Patented Apr. 4, 1922.

Application filed August 15, 1919. Serial No. 317,781.

To all whom it may concern:

Be it known that I, ALFRED G. HAGUE, a citizen of the United States, residing at Adel, in the county of Dallas, State of Iowa, have invented an Off-Bearing Mechanism for Tile Cutters, of which the following is the specification.

This invention relates to the clay industry and particularly to a mechanism for moving 10 hollow building blocks or drain tile from a cutter table while in a plastic condition, and placing the same on an endless conveyor in a substantially vertical position.

The object of my invention is to provide 15 an off-bearing mechanism for tile cutters of simple, durable and inexpensive construction, adapted to automatically remove plastic blocks or tile from a cutting table and place the same on a separate conveyor.

20 A further object is to provide in an off-bearing mechanism for tile cutters, new and improved method of grasping plastic tile or blocks.

A still further object is to provide an off-25 bearing mechanism driven by independent power and timed to the cutting table in such a manner as not to materially increase the power required to move the conveyor of the said cutting table.

30 A further object is to provide in an off-bearing mechanism, means whereby the plastic tile or hollow blocks and the like may be quickly and firmly grasped and removed from the cutter table without crushing or warping 35 the walls of the said tile or blocks.

There are other objects which will be apparent to those skilled in the art and which need not be enumerated in detail.

My invention consists in the construction, 40 arrangement and combination of the various parts of the device, whereby the objects contemplated are attained as hereinafter more fully set forth, pointed out in my claims, and illustrated in the accompanying drawings, in which:

Fig. 1 is a side elevation of my off-bearing mechanism showing the manner in which it is mounted relative to the cutter table and the horizontal conveyor.

50 Fig. 2 is an end elevation of the same with the horizontal conveyor removed.

Fig. 3 is a perspective view of one of the grippers showing a portion of the air tube attached.

Fig. 4 is a transverse sectional view of said 55 grippers taken on the line 4—4 of Fig. 3.

Fig. 5 is a sectional view of the operating cylinder and its controlling valve.

Fig. 6 is a transverse sectional view of one 60 of the timing and controlling valves for the grippers.

Fig. 7 is a longitudinal sectional view of 65 said timing valve taken on the line 7—7 of Fig. 6.

Fig. 8 is an end elevation of the timing 70 valve showing the manner in which the operating arm is attached.

Fig. 9 is a longitudinal sectional view of 75 the controlling valve showing the air ports, and is taken on the line 9—9 of Fig. 8.

Fig. 10 is an end elevation of the timing 80 valve showing the operating lever in segment.

Fig. 11 is a longitudinal sectional view of 85 the timing valve showing the air recesses taken on the line 11—11 of Fig. 10. Also showing the position of the air ports.

Fig. 12 is a detail end view of one of the 90 cams for actuating the timing valve.

Fig. 13 is a detail view showing the operating arm for the timing valve in position relative to one of the guide arms of the cutter conveyor.

Referring to the accompanying drawings, the reference numeral 10 indicates the side 95 of a cutting table having legs 11 and a conveyor 12. The conveyor 12 is formed of links 13, and transverse plates 14, each alternate plate 14 is provided at each end with a guide arm 15 and each intermediate plate 14 is provided at each end with a short guide 100 arm 16. Each of the links 13 is provided with a roller 17 designed to run in a channel or track 18, provided on the inner face of each of said side members 10. Each of the alternate plates 14 is designed to carry a pallet 19, each of said pallets being designed to carry a plastic block or tile, one of the blocks being shown in position in Fig. 2 of the drawings. The pallets illustrated are 105 flat on top and designed to carry rectangular building blocks, but when it is desired to

cut and carry drain tile, a pallet with a concave face is provided, in place of the flat faced pallets.

The sides of the cutter table are of considerable length, and for that reason the pallets of the conveyor 12 lie in a horizontal plane as they move across the top portion of said table, and are of such a width as to nearly touch when in said horizontal position. The column of plastic material is fed horizontally upon the top faces of said pallets, the conveyor 12 is moved horizontally in the tracks 18 by frictional contact between the tops of the pallets 19 and said plastic column.

On account of the column being in a plastic condition, it is not desirable to apply any load or pressure to the conveyor other than the weight of the column. For that reason it is desirable, in machines of this class, to operate the off-bearing mechanism independently. As the column of plastic material reaches a point near the delivery end of the table, they are cut into short lengths forming blocks or tile. When the pallets have reached the end of the cutter table, they momentarily take a position on an angle, as illustrated in Fig. 1, of about forty degrees with a horizontal line. This is approximately the proper position to remove the block from the cutter conveyor, and also the proper position in which the block should assume to allow the cutter wires to clear the rear end of the block. At this angle the blocks will not slide off of the pallets, and for that reason I have designed my machine to remove the blocks at the angle illustrated.

Near the delivery end of the table 10, I have provided a horizontal conveyor 20, having a belt 21 in line with the conveyor 12 and in a plane considerable lower than the said cutter conveyor. This conveyor 20 is for the purpose of receiving the plastic blocks or tile on end, in an upright position, from the table 10. The belt 21 is driven by any suitable power and at a speed considerably higher than the side of the conveyor 12, for the purpose of separating the blocks so that they may be easily grasped by operators as they are removed from said conveyor 21, and placed on drier cars.

This cutter table and horizontal conveyor are of the ordinary construction and form no particular part of my invention, and are illustrated to show the operative relation between my device and said conveyors.

To remove the plastic blocks from the pallets 19 and place them on the conveyor belt 21 automatically, I have provided the following mechanism.

Mounted between the legs 11 and beneath the delivery end of the cutter frame 10, I have provided a frame 22.

The frame 22 is provided with upright supports 23; the upper ends of which have

rotatively mounted thereon a transverse shaft 24. The shaft 24 is provided at each end with an upright arm 25, the upper ends of which are tapered and extend upward and rearward. A curved portion is formed 70 at 26 for the purpose of clearing the conveyor 12, at the end of the table.

The uprights 25 are so spaced that they may be moved between the guide arms 15 and past the ends of the pallets 19, the said pallets being a considerable shorter than the length of the plates 14. The supports 25 are for the purpose of carrying what I shall term, grippers, designed to pick up blocks from the pallets 19 and release them when 80 in the proper position over the belt 21. Each of said grippers comprise a plate 27, (Figs. 3 and 4) having slanting flanges 28 and parallel flanges 29. The flanges 29 are provided with screw threaded openings 30. The said grippers are formed right and left and each provided with a tapering socket 31 designed to receive the upper end of said supports 25. A set screw 33 is provided in the lower edge of the socket 31 for the purpose 90 of locking the gripping devices in position. An air chamber 34 is provided adjacent to said socket and is designed to enter in communication with a flexible hose 35, the free end of which is provided with a coupling 36. The chamber 34 is in communication with the pocket 37 formed by the plate 27 and the flanges 28. For each of the pockets 37, I have provided a diaphragm 38 formed of flexible material such as rubber or leather, 100 secured to the flange portion 29 by means of metal strips 39, and screws 40, in the holes 30. By this arrangement, an air pocket 37 is formed, and communicates with the chamber 34 through the slot 41.

It will thus be seen that if air or any suitable gas be forced into the chamber 34 and into the pocket 37 through the slot 41, the diaphragm 38 will be forced outward to the position shown in Fig. 4. If the said 110 air or gas is sucked out by a vacuum or exhausted, the diaphragm will collapse, due to the atmospheric pressure.

It is evident that if two of these gripping devices are spaced apart and clamped to the 115 ends of the supports 25 with their diaphragms facing each other a distance greater than the width of the block to be removed, and if air is admitted to the pockets 37, the said diaphragms will expand toward each 120 other and engage the adjacent edges of a block or tile, placed between them, and firmly grasp the same. The pressure will be evenly distributed over the surface engaged by said diaphragms, the area of said diaphragms being of such size that the initial pressure may be low, and the crushing, or warping of the walls, of the plastic blocks prevented. On account of the diaphragm being pliable and flexible, it will adjust 130

itself readily to slight variations in widths and uneven surfaces without injurious effects to said surfaces.

For controlling and supplying air to the 5 said grippers, I have provided a compressed air pipe 42, a suction or vacuum pipe 43 and a controlling valve 44. The air pipe 42 may be attached to a suitable compressed air tank, not shown in the drawings, and having the 10 regular controlling and pressure regulating devices. In this connection it may be noted that by adjusting the pressure regulating devices, the grippers may be quickly and accurately adjusted to take care of blocks 15 of different weights, the heavier block requiring more air pressure than the lighter one. Likewise the vacuum pipe 43 is designed to be attached to a suitable vacuum tank, said tank to be equipped with the ordinary regulating devices. The said pipes are provided with a controlling valve, comprising a body portion 44 having a flange 45, said flange being provided with a slot 46, which is for the purpose of adjustably 20 mounting the valves to the supports 25 by means of bolts 47. The said body portion is also provided with cylindrical air chambers 48 closed at their upper ends and provided at their lower ends with shoulder portions 25 49, each of which is designed to receive a flexible hose, 42 and 43. Parallel to the said air chamber 48 is a cylindrical valve chamber 50 having longitudinal slots 51 and 52 in communication with the chambers 48 (Figs. 35 6 and 11).

The chamber 50 is designed to receive a valve 53 having a stem 54 and ports 55 and 56 in communication with the longitudinal opening 57 of the valve 53. The ports 55 40 and 56 are spaced apart a distance greater than the slots 51 and 52 and for that reason, when the slot 52 and the port 55 are in communication, the slot 51 and the port 56 will be out of line with each other, as illustrated 45 in Fig. 6. This will close the slot 51. If the valve 53 is rotated in a counter-clockwise direction, the port 56 will be moved in line with the slot 51 and the slot 52 closed. I have provided a coupling member 58 designed to be secured into the end of the valve chamber 50, as illustrated in Fig. 7. This 50 coupling member 58 is designed to make connection with the member 36 before described.

55 By this arrangement, the pocket 37 may be in communication with either of the pipes 42 or 43 by an oscillating movement of the valve 53.

For actuating the valve 53, I have provided 60 a lever 59 secured to the valve stem 54 by means of the key 60. The lever 59 is provided at one end with a cam 61 and at the other with the cam 62, the cam 61 being designed to lie in the path of the guide arm 65 16 when the grippers are in the position

shown in Fig. 1. In this position the exhaust or vacuum pipe is in communication with the diaphragm.

As the conveyor 12 is rotated, the arm 16 will engage the cam 61 and cause the valve 57 to be rotated and moved to the position shown in Fig. 6 of the drawings, with the slot 52 in line with the port 55. Compressed air is admitted to the diaphragms, which causes them to expand and grasp the block, 75 the further operation of which will herein-after be more fully set forth.

Extending upward from the base 22, I have provided a support 63 designed to carry an operating cylinder 64, the said cylinder 80 64 is mounted in a head 65, having lugs 66 which are pivotally secured to the upper end of the member 63. One side of the member 65 is provided with a valve seat 67, having ports 68 and 69. The air port 68 is designed to communicate with the inside of the cylinder 64, while the port 69 is designed to communicate with the atmosphere. A valve chest 70 is provided for the seat 67 and has a projection 71 provided with an 85 opening 72. The opposite end of the chest is provided with a packing gland 73, in which is slidably mounted a rod 74, the opposite end of the rod being slidably mounted in the opening 72. The valve 75 is provided for the seat 67, which is similar to those used on the steam engines, and has a port 76 90 designed to communicate with the ports 68 and 69.

The opposite end of the cylinder 64 is 100 provided with a head 76 having an opening 77 to permit free movement of the air due to the action of the piston 78. The said piston is provided with the regular packing 79 and is secured to one end of a rod 80 by 105 means of a nut 81.

Secured to the central portion of the shaft 24, I have provided an arm 82, the central portion of which is designed to carry the upper end of the rod 80, said rod being 110 pivotally connected thereto by means of a pivot 83. The upper end of the rod 80 has a shoulder 84 against which rests a spring 85, the lower end of which rests on the head 76. This spring 85 is for the purpose of 115 counter-balancing the weight of the grippers together with the supporting arms when the said grippers are in a delivery position.

Pivotally connected to the outer end of the rod 74, is a rod 86, provided with adjusting nuts 87 and 88. The said rod 86 is slidably mounted in the free end of the arm 82.

I have provided a pipe 89 in communication with the chest 70 and with the flexible 125 hose 42. In practical operation, assuming that the flexible hose 42 is connected to a compressed air tank and in communication therewith, and the pipe 43 is in communication with the vacuum tank, and that the 130

block from the cutting table has been delivered to the position shown in Fig. 1 of the drawings, and that the valve 57 is in a position with the slot 51 in communication with the port 56: This will permit the cam 61 to lie in the path of the arm 16, as illustrated in said figure. The diaphragms will then be in communication with the vacuum tank and be in a collapsed position, permitting the said block to move freely between them. As the conveyor 12 is advanced, the arm 16 will engage the cam 61 and cause the valve 57 to be rocked or rotated to the position shown in Fig. 6 with the slot 52 and the port 55 in line with each other. This will permit compressed air from the pipe 42 to enter the pocket 37 back of the diaphragms and cause them to be expanded toward each other and to grip the block. The valve 75 will be in the position shown in Fig. 5, with the piston 78 in its upper position of movement. As the pallet 19 is advanced, it will move the block and the grippers forward until the said block has passed a vertical center through the shaft 24, after which gravity will move the arms 25 to the position shown by dotted lines, in Fig. 1. The piston 78 will have moved downwardly in the cylinder 64 and the contained air therein exhausted through the ports 68 and 69. The free end of the arm 82 will slide down the shaft 86 and engage the nuts 87, causing the valve 75 to be moved downward until the upper edge of said valve passes the port 68. This will permit compressed air from the pipe 89 to enter the cylinder 64 and form a cushion with the downward movement of said piston, and also for taking the inertia of the arms 25. Just before the arms 25 have reached the position shown by dotted lines, the cam 62 of the arm 59 will engage a cam 90, which is adjustably secured to the side of the conveyor frame 20. This cam 90 will cause the valve 57 to be rotated so that the ports 51 and 56 are in communication. This will cause the diaphragms 83 to collapse inasmuch as the port is in communication with the vacuum tank through the pipes 43. The collapsing of said diaphragms will permit the block to be released in an upright position on the conveyor belt 21. The compressed air within the cylinder 64 will move the piston 78 upward, causing the arms 25 to return to their normal position, the movement of which is limited by means of a set screw 91 engaging an arm 92 mounted on the shaft 24. The arms 25 will rest in this position until another guide arm 16 engages the cam 61 as before described. It will be seen by this arrangement, I have provided an accurate means of timing the movement of the grippers with the conveyor without materially adding any friction to the said conveyor. The valve 57 may be accurately timed with the movement of the

pallet 19 by the adjusting bolt 47 and the slot 46. The delivery of the blocks may be timed by adjusting the cam 91 relative to the side of the frame 20 by means of the nuts 95 and the slot 96. The timing of the valve 75 is accomplished by adjusting the nuts 87 and 88 on the rod 86. By adjusting these nuts, the proper timing of the said valve may be accomplished so that the cushion effected may be imparted to the arms 25.

Grippers of different shapes or sizes may be provided to adapt them to tile of different shapes and sizes and may be used in the place of the one shown in the drawings, and may be secured to or detached by means of nuts 33 and the coupling 36.

Thus it will be seen that I have provided an off-bearing mechanism for block and tile cutters of comparatively simple construction which may be accurately timed to operate with the conveyor of the cutter table without imparting any additional load thereto.

I claim:

1. In a device of the class described, spaced pneumatic grippers each having a diaphragm on its inner face, a support for said grippers, means for moving said grippers from a delivery position to a receiving position, means for admitting compressed air to the back of each diaphragm when in a receiving position, and means for producing a partial vacuum back of said diaphragm when in a delivery position.

2. In a device of the class described, spaced pneumatic grippers, each having a diaphragm on its inner face, a support for said grippers, means for moving said grippers from a delivery position to a receiving position, means for limiting the movement of said grippers in one direction, means for admitting compressed air to the back of each diaphragm when in a receiving position, and means for producing a partial vacuum back of said diaphragms when in a delivery position.

3. In a device of the class described, spaced pneumatic grippers, each having a diaphragm on its inner face, a support for said grippers, means for expanding and contracting each of said diaphragms comprising a compressed air pipe, a vacuum pipe, a valve capable of communicating with said diaphragm and capable of communicating with either of said pipes, means for moving the valve in communication with the compressed air pipe when the diaphragm is in a receiving position and means for moving the valve in communication with the vacuum pipe when the diaphragm is in a delivery position, and means for moving said grippers from a delivery position to a receiving position.

4. In a device of the class described, spaced pneumatic grippers each having a diaphragm on its inner face, a support for

said grippers, means for detachably connecting said grippers to said support, means for moving said grippers from a delivery position to a receiving position, means for 5 limiting the movement of said grippers in one direction, means for admitting compressed air to the backs of said diaphragms when in a receiving position, and means for producing a partial vacuum back of said 10 diaphragms when in a delivery position.

5. In a device of the class described, spaced pneumatic grippers, each having a diaphragm on its inner face, and capable of movement from a receiving position to a 15 delivery position or vice versa, an oscillating support for carrying said grippers, comprising upright arms pivotally mounted substantially beneath the receiving position of said grippers, means for detachably connecting said grippers to said supports, means for producing a partial vacuum back of said 20 diaphragms when in a delivery position, and means for admitting compressed air to the back of each diaphragm when in a receiving 25 position.

6. In a device of the class described, spaced pneumatic grippers, having a diaphragm on each inner face, and capable of movement from a receiving position to a delivery position, means for moving the grippers from a receiving position to a delivery position, means for admitting compressed air to the back of each diaphragm when in a receiving position, and means for producing a partial vacuum back of each diaphragm when in a delivery position, for the purpose stated.

7. In a device of the class described, spaced pneumatic grippers each having a diaphragm on its inner face, and capable of movement from a receiving position to a delivery position, an oscillating support comprising upright arms pivotally mounted substantially beneath the receiving position of 45 said grippers, means for moving the grippers from a receiving position to a delivery position, pneumatic means for moving said grippers from a delivery position to a receiving position, means for admitting compressed air to the back of each of said diaphragms when in a receiving position, and means for producing a partial vacuum back of each diaphragm when in a delivery position, for the purpose stated.

55 8. In a device of the class described, spaced pneumatic grippers, each having a diaphragm on its inner face and capable of movement from a receiving position to a delivery position, an oscillating support 60 comprising upright arms pivotally mounted substantially beneath the receiving position of said grippers, means for moving the grippers from a receiving position to a delivery position, pneumatic means for moving said 65 grippers from a delivery position to a re-

ceiving position, means for detachably connecting said grippers to said support, means for admitting compressed air to the back of each of said diaphragms when in a receiving position, and means for producing a partial vacuum back of each diaphragm when in a delivery position, for the purpose stated.

9. In a device of the class described, spaced pneumatic grippers, each having a diaphragm on its inner face, a support for said grippers, means for expanding and contracting each of said diaphragms comprising, a compressed air pipe, a vacuum pipe, a valve capable of communicating with said diaphragm and capable of communicating with either of said pipes, means for moving the valve in communication with the compressed air pipe when the diaphragm is in a receiving position, means for moving the valve in communication with the vacuum pipe when the diaphragm is in a delivery position, means for moving the grippers from a receiving position to a delivery position, and pneumatic means for moving said grippers from a delivery position to a receiving position.

10. In a device of the class described, spaced pneumatic grippers, each having a diaphragm on its inner face, and capable of movement from a receiving position to a delivery position, an oscillating support comprising upright arms pivotally mounted substantially beneath the receiving position of said grippers, means for expanding and contracting each of said diaphragms comprising, a compressed air pipe, a vacuum pipe, a valve capable of communicating with said diaphragm and capable of communicating with either of said pipes, means for moving the valve in communication with the compressed air pipe when the diaphragm is in a receiving position, means for moving the valve in communication with the vacuum pipe when the diaphragm is in a delivery position, means for moving the grippers from a receiving position to a delivery position, and pneumatic means for moving said grippers from a delivery position to a receiving position.

11. In a device of the class described, spaced pneumatic grippers, each having a diaphragm on its inner face, a support for said grippers, means for expanding and contracting each of said diaphragms comprising, a compressed air pipe, a vacuum pipe, a valve capable of communicating with said diaphragm and capable of communicating with either of said pipes, means for moving the valve in communication with the compressed air pipe when the diaphragm is in a receiving position, means for moving the valve in communication with the vacuum pipe when the diaphragm is in a delivery position, pneumatic means for mov-

ing said grippers from a delivery position to a receiving position, and yielding means for balancing the weight of said gripping devices and holding them to a normal position.

12. In a device of the class described, spaced pneumatic grippers, each having a diaphragm on its inner face, a support for said grippers, means for moving said grippers from a delivery position to a receiving position, means for admitting compressed air to the back of each diaphragm when in a receiving position, means for producing a partial vacuum back of said diaphragms when in a delivery position, yielding means for balancing the weight of said grippers and holding them in a normal position for the purpose stated.

13. In a device of the class described, spaced pneumatic grippers, each having a diaphragm on its inner face, a support for said grippers, means for moving said gri-

pers from a delivery position to a receiving position and means for admitting compressed air to the back of each diaphragm 25 when in a receiving position.

14. In a device of the class described, a supporting member capable of movement from a receiving position to a delivery position, pneumatic grippers on said support, 30 means for actuating the grippers to grasp a block of plastic material, means for actuating said support, and means for actuating the grippers to release said block.

15. In a device of the class described, 35 spaced pneumatic grippers having means for supporting and moving them from a receiving position to a delivery position, and vice versa, and means for actuating said grippers when in a receiving position to 40 grasp a plastic block, or brick, and to deliver the same when in a delivery position.

ALFRED G. HAGUE.
